UNITED STATES PATENT OFFICE.

DE WITT C. RELYEAE, OF COSCOB, CONNECTICUT.

OPENER FOR GLASS-TOPPED JARS.

1,279,441.

Specification of Letters Patent. Patented Sept. 17, 1918.

Application filed March 7, 1918. Serial No. 220,981.

To all whom it may concern:

Be it known that I, DE WITT C. RELYEAE, a citizen of the United States, and a resident of Coscob, in the county of Fairfield and 5 State of Connecticut, have invented a new and Improved Opener for Glass-Topped Jars, of which the following is a full, clear, and exact description.

This invention relates to household devices 10 and has particular reference to means for opening fruit jars or the like.

More definitely stated the primary object of the invention is to provide means for 15 easily, quickly and safely lifting or removing the glass top of a vacuum sealed fruit jar, or its equivalent.

The process of preserving fruit by means 20 of jars having lids or covers held by internal vacuum is now so fast taking the place of the previously used screw tops, that it is important to provide a means whereby the 25 glass top so held may be lifted or the vacuum broken without danger or injury to the operator or likelihood of chipping or breaking any portion of the cover or jar. Since 30 the cover is of glass, or its equivalent, as distinguished from a metal top, it cannot be punctured for the purpose of admitting air, and hence a tool, such as a sharp knife point 35 or the like, is commonly introduced beneath the edge of the cover, a dangerous and troublesome expedient.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is had to the accompanying drawings, in which like 45 reference characters designate the same parts in the several views, and in which—

Figure 1 is a plan view of my complete 50 device showing the parts adjusted for application to a large jar cover and indicating in dotted lines the adjustment for a smaller jar cover.

Fig. 2 is a sectional detail on the line 2—2 55 of Fig. 1.

Fig. 3 is a perspective detail view of the anchor member; and

Fig. 4 is a vertical sectional view of a glass 60 jar and its cover, and indicating the point of application of the hoop.

Referring now more particularly to the drawings I show my device as comprising three principal parts, first, a rigid handle or lever 10 made preferably of straight flat material; a hoop 11 of multiple-strand or 60 twisted wire or cable, and an anchor member 12.

One end of the hoop is provided with a loop 13 through which a clevis 14 projects, said clevis being connected to the end of the 65 lever 10 by means of a pivot member 15 shown as a rivet, or its equivalent, having relatively flat or rounded ends and projecting through a hole 16 in the end of the lever. The clevis thus is adapted for free rotation 70 around the axis of the pivot for coöperation on either side of the lever. The length of the hoop is proportioned to standard sizes of fruit jars, and to its other end is fixed the anchor member 12 shown in detail in Fig. 3 75 and in operation in Fig. 1.

The anchor comprises a rigid piece of heavy wire or jar metal bent upon itself forming a loop or eye 17, but with one free end longer than the other. The two leg portions 18 and 19 of the anchor are of unequal 80 length though they lie against each other and in the same plane. Each leg terminates in a hook 18' or 19' respectively but the hooks project in opposite directions from 85 the plane of the legs.

The lever not far remote from the pivot 15 is provided with a plurality of holes 20 in any one of which either of the hooks of the anchor is adapted to be inserted according to the precise length of the hoop or the amount of leverage required to effect the purpose. In any event, however, the effective length of the lever between the pivot 15 and the point of application of the hook is 90 relatively short so that when the parts are connected and slipped for the top 21 of the jar 22 just outside of the gasket 23 and the longer end of the lever is moved in the direction of the arrow thereon the hoop will 95 wedge or cut its way directly in between the cap flange and the shoulder of the jar and since the hoop is made of multiple-strand wire cable air is admitted freely through and past it beneath the cap flange the moment 100 the cap begins to lift. Obviously as soon as air is admitted the cap may be freely lifted by hand from the jar. With the device applied as indicated it is impossible even for 105 a novice to either crush, break or chip any 110

2
part of the jar or its cover, and yet with the application of very little force a cap held by a high degree of vacuum may be readily lifted or removed.

5 It will be noted that since the hoop is flexible and is connected to turn freely about the end of the lever it is expedient for the device to be applied either as a right handed or left handed tool, the operation being just 10 the same. The rounded anchorage end of the lever, at or within the clevis, engages directly against the rubber gasket when force is applied to the handle end of the lever, and so while such rounded end or 15 point may enter slightly beneath the cap, the rounded rivet heads coming into contact with the periphery of the cap and adjacent shoulder part of the jar act as limiting stops to prevent any part of the device

from chipping, crushing, or cracking the 20 glass.

I claim:

A glass jar cover lifter, comprising a rigid lever having a rounded end and provided adjacent said end with a plurality of 25 openings, a clevis pivoted to the rounded end of the lever, a multiple strand wire cable having one end secured to the clevis, and an anchoring member comprising a piece of wire bent upon itself to form an eye to 30 which the other end of the cable is secured and two parallel members of unequal length, each terminating in a hook adapted to engage an opening of the lever, the hooks projecting in opposite directions from the plane 35 of the members.

DE WITT C. RELYEA.
